UNITED STATES PATENT OFFICE.

WILLIAM J. GOING, OF AMSTERDAM, NEW YORK, ASSIGNOR TO KLAUDER-WELDON
DYEING MACHINE CO., OF YARDLEY, PENNSYLVANIA, A CORPORATION OF NEW
YORK.

YARN-TREATING MACHINE.

1,287,962.

Specification of Letters Patent. Patented Dec. 17, 1918.

Original application filed March 11, 1915, Serial No. 13,596. Divided and this application filed April 6, 1916.
Serial No. 89,260.

To all whom it may concern:

Be it known that I, WILLIAM J. GOING, a citizen of the United States, residing at Amsterdam, in the county of Montgomery 5 and State of New York, have invented certain new and useful Improvements in Yarn-Treating Machines, of which the following is a full, clear, and exact description, such as will enable others skilled in the art to which 10 it appertains to make and use the same.

This invention relates to apparatus for treating yarn, and with respect to its more specific features to apparatus of the character referred to involving rolls for squeezing 15 yarn. It has for its object to overcome some of the difficulties which have arisen in connection with prior machines.

One of the objects of the invention is to provide a practical construction of squeezing 20 roll, the surface of which may be renewed without removing the entire roll from the machine.

Another object of the invention is the provision of a simple construction permitting 25 the roll to be resurfaced readily by even unskilled operators.

Another object of the invention is to provide an efficient mechanical arrangement of 30 squeezing rolls.

Other objects will be in part obvious and in part pointed out hereinafter.

The invention accordingly consists in the features of construction, combinations of elements and arrangement of parts which will 35 be exemplified in the construction herein-after set forth, and the scope of the application of which will be indicated in the following claims.

In the accompanying drawings forming 40 part of this specification and wherein similar reference characters refer to similar parts throughout the several views,—

Figure 1 is an elevation of an embodiment 45 of the invention;

Fig. 2 is a plan view of a portion of Fig. 1; and

Fig. 3 is a sectional elevation of a portion 50 of Fig. 1.

The machines herein referred to are generally in the form of rectangular vats containing various yarn treating liquids, such as water, dye, and various other solutions dependent upon the treatment to which the

yarn is subjected. The squeezing rolls forming part of such machines are usually covered with rubber. When they deteriorate or wear out they must be removed from the machine and sent to experts for recovering. This requires substitute rolls to be at hand, or that the machine remain idle until the rolls are repaired or renewed. This application is a division of application filed March 11, 1915, Serial No. 13,596 (1915), and reference may be had thereto for a disclosure of the complete machine. For the purposes of this case, it is sufficient to describe herein only a part of the machine of the prior case, and referring more specifically to the drawings, the numeral 1 indicates a tank or vat, in which the yarn treating liquid is contained. The yarn is carried through the liquid in the vat by aprons, the parts of two of such aprons adjacent the squeezing rolls being shown at 2, 2, it being understood that these aprons are automatically driven to convey the yarn through the liquid in the tank, and to deliver the yarn to the pair of squeezing rolls 3 and 4. In the present embodiment the yarn leaves the tank on the right hand side as the apron 70 passes over the sprocket 5. Upon leaving the apron or conveyer at this sprocket, it passes from the machine between the squeezing rolls. The rolls 3 and 4 are driven from the worm gear 6 through the shaft 7, the upper roll being turned by the gear 8, taking its motion from gear 9 on the shaft 7. The lower roll has a stationary bearing in the frame or frame pieces 10, but the upper roll has sliding box bearings 11 in guideways 12 in the frame pieces, and these box 75 bearings are forced down by levers 13 fulcrumed on the frame piece 10, these levers having lugs 14 which press down the sliding boxes of the roller 3 by springs 15 secured to rods 16, pivoted at 17 in said frame pieces and bearing upon the eye 18 in the end of the lever 13. A nut and lock nut 19 determine the tension of the spring.

The construction of the rolls is indicated in Fig. 3. A slot is cut in the supporting metal portion 3, for example, and in this slot is removably secured, by means of a rod 20 of wood, the inner end or portion of a suitable sheet of textile material 21, which is to form 105 a cover for the roll. The machine is then

allowed to operate and the roll rotates until a sufficient thickness of the material, in the judgment of the operator, is wrapped or coiled upon it when the end is cut off. No 5 securing means for this end is ordinarily necessary, because when the wet yarn is squeezed the whole absorbent covering becomes soaked with the treating liquid and the end remains in place, being held by the 10 adhesion produced by the liquid squeezed from the material to be treated. The material which is used and preferred is sail cloth or canvas, as it is found that when this material gets wet, it is soft enough not to injure the yarn, and yet it has sufficient bite 15 to grip the yarn and carry it through the rolls easily. As will be manifest, it will not be necessary to remove the rolls from the machine for recovering, since the old covering 20 may be cut off from them and the stick 20 may be pulled out or be driven out from one end and removed by a few taps of a hammer.

During the operation of squeezing, the rolls are rotated in directions tending to 25 maintain the covering in coiled condition, these rolls, as it were, operating to continually wrap or coil the covering, so that the yarn received between the rolls may be effectively squeezed without causing the un- 30 wrapping or uncoiling of the covering. In Fig. 3 the arrows indicate the direction of rotation of the rolls during squeezing, and the numeral 22 indicates the outer free end of the coiled covering in position freely over- 35 lying or overlapping the turn, or portion of the coil, therebeneath. The worm wheel 6 is driven by the worm 23, in turn rotated from any suitable source of power.

As many changes could be made in the 40 above construction and many apparently widely different embodiments of this invention could be made without departing from the scope thereof, it is intended that all matter contained in the above description or 45 shown in the accompanying drawings shall be interpreted as illustrative and not in a limiting sense.

It is also to be understood that the language used in the following claims is intended 50 to cover all of the generic and specific features of the invention herein described, and all statements of the scope of the invention, which, as a matter of language, might be said to fall therebetween.

Having described my invention, what I 55 claim as new and desire to secure by Letters Patent is:

1. In a yarn treating machine, a tank adapted to contain a yarn treating liquid, a 60 pair of squeeze rolls, means adapted to con-

vey yarn from said tank to said rolls, one of said rolls comprising a covering of absorbent material coiled therearound, one turn overlapping another, and means adapted to rotate said rolls in directions tending to maintain said covering in coiled condition during the squeezing operation. 65

2. In a yarn treating machine, a tank adapted to contain a yarn treating liquid, a pair of squeeze rolls, means adapted to convey yarn from said tank to said rolls, one of said rolls comprising a covering of absorbent material coiled therearound, one turn overlapping another, an inner portion of said coiled covering being removably connected to its roll, the outer end of said covering being free, and means adapted to rotate said rolls in directions tending to maintain said covering in coiled condition during the squeezing operation. 70 75

3. In a yarn treating machine, a tank adapted to contain a yarn treating liquid, a pair of squeeze rolls, means adapted to convey yarn from said tank to said rolls, one of said rolls having a covering of absorbent material coiled therearound, one turn overlapping another, means adapted to rotate said rolls in directions tending to maintain said covering in coiled condition during the squeezing operation, and means adapted to 80 85 yieldingly press one of said rolls toward the other.

4. As a new article of manufacture, a squeezing roll for a yarn treating machine, comprising a support and a cover, the latter 95 comprising a sheet of fabric coiled on said support and adapted to be readily uncoiled therefrom, one turn overlying freely on another.

5. As a new article of manufacture, a 100 squeezing roll for a yarn treating machine composed of a support, and a cover, the cover composed of several thicknesses of sail cloth or canvas, continuously wrapped around the supporting structure and secured 105 at one end thereto, the other end of the cover being unsecured.

6. As a new article of manufacture, a roll for a yarn treating machine comprising a support, and a cover, the cover composed of 110 a textile sheet removably secured at one end to the support and wrapped thereabout, the wrappings lying freely on each other so as to be readily unwrapped from the outside.

In testimony whereof I affix my signature, 115 in the presence of two witnesses.

WILLIAM J. GOING.
